UNITED STATES PATENT OFFICE

109,675

DESIGN FOR A TUMBLER OR SIMILAR ARTICLE

Thomas D. Saunders, Dunbar, W. Va., assignor to Dunbar Glass Corporation, a corporation of West Virginia

Application March 16, 1938, Serial No. 75,874

Term of patent 7 years

To all whom it may concern:

Be it known that I, Thomas D. Saunders, a citizen of the United States, residing at Dunbar, in the county of Kanawha and State of West Virginia, have invented a new, original, and ornamental Design for a Tumbler or Similar Article, of which the following is a specification, reference being had to the accompanying drawing, forming part thereof, in which Figs. 1, 2, and 3 are side elevational, top plan, and bottom plan views, respectively, showing my new design.

I claim:

The ornamental design for a tumbler or similar article, substantially as shown.

THOMAS D. SAUNDERS.
